(57) **CLAIM**

The ornamental design for an electronic score keeping device, as shown and described.

DESCRIPTION

FIG. 1 is a perspective view of the electronic score keeping device of my new design.

FIG. 2. Is a front elevational view thereof.

FIG. 3 is a back elevational view thereof.

FIG. 4 is a right side elevational view thereof.

FIG. 5 is a left side elevational view.

FIG. 6 is a top plan view thereof; and,

FIG. 7 is a bottom plan view thereof.

The two devices outlined in broken lines which are shown in FIG. 1, are environmental elements and form no part of my new design.

1 Claim, 6 Drawing Sheets

FIG.2

FIG.3

FIG. 5

FIG. 4

FIG. 6

FIG. 7
